UNITED STATES PATENT OFFICE.

JAMES E. TWITCHELL, OF DETROIT, MICHIGAN, ASSIGNOR, BY MESNE ASSIGNMENTS, TO J. B. TIMBERLAKE & SONS, OF JACKSON, MICHIGAN.

DISPLAY-EASEL.

No. 895,211.

Specification of Letters Patent.

Patented Aug. 4, 1908.

Application filed March 15, 1905. Serial No. 250,215.

To all whom it may concern:

Be it known that I, JAMES E. TWITCHELL, a citizen of the United States, residing at Detroit, in the county of Wayne and State of Michigan, have invented certain new and useful Improvements in Display-Easels, of which the following is a specification, reference being had therein to the accompanying drawing.

10 This invention relates to stands or supports for dishes and other articles, particularly and of the class referred to as "display easels" and largely used for exhibition purposes.

15 It has for its object to provide an article of this class which can have its parts so adjusted as that it can be used for displaying or supporting either of several styles of articles, or either of several articles differing from 20 each other in size.

In the drawings:—Figure 1 is a perspective of an easel, the holder embodying my improvements. Fig. 2 is a side view with the parts in one extreme position of adjustment. Fig. 3 is a side view with the parts at the other extreme of adjustment. In Figs. 2 and 3 the plates supported by the easel are represented in dotted lines. Fig. 4 is a side view showing in full lines the parts in an intermediate adjustment and in dotted lines in its extreme positions.

The article which I have selected for illustration in the drawings is composed of two principal elements, one being situated at the 35 front and the other at the rear, the former being intended to engage with the lower front part of a dish or similar article and the latter to engage with and support the back or upper part. One of these elements is indicated 40 by A, it being of U-shape and having vertical legs a, a, a connecting cross loop a' at the top and feet a² at the lower ends of the leg parts. This rear or back supporting element can be formed of a single piece of wire bent into a 45 U-shape, or approximate U-shape, as shown. The feet are provided by forming eyes or loops a³ at the lower ends of the wire and by preference a bend is formed in each leg at a⁴ so as to provide short arms a⁵.

50 The forward element of the device is indicated by B. It has two side bars or arms b, b, and at the front end a cross connection c consisting preferably of two downwardly extending bends c' and an upwardly curved

cross bar or arm c² connecting the downwardly bent parts.

At the rear elongated connecting devices C are provided for joining the front element to the rear. Preferably these are formed by making several helical bends, twists or coils in the end parts of the side bars b. These connecting devices loosely encircle the legs a of the rear or back supporting element of the device. By having elongated joining devices of this character I provide parts which act as a lock or gripper to hold the two elements firmly in either of the several positions of adjustment to which they can be moved. Thus in Fig. 2 they are shown with the front element in its lowest adjustment, 70 connecting devices at C at this time being at the lower ends of the legs a and bearing upon the bent short arms a⁵. When they are in such position a heavy article, or one of large diameter, can be placed on the easel and 75 firmly supported. For instance, a large plate or dish can be securely held, its front end being placed and bearing against the loop part c² of the front element of the easel, while the back of the dish rests against the 80 loop part a' of the rear element.

If it is desired to use the holder or easel to support a smaller or lighter article the parts are put into the position shown in Fig. 3, the joining devices at C being readily slipped up 85 to the upper position, and because of their being elongated they engage with the legs a, a, at two remote points and provide a strong grip that prevents either element from slipping as to the other. Similarly, other articles differing in size, shape or weight from 90 those referred to can be supported when the parts of the easel are adjusted to any of the intermediate positions, such as shown in Fig. 4.

95 It will be seen that when the two elements of the device are in any position above that shown in Fig. 2 the lines of the side bars b, b, and of the vertical legs a, a, are inclined to the horizontal in such way that whatever 100 weight is being supported upon the easel tends to spread or separate the front feet from the rear ones and this causes the connecting devices C to firmly engage frictionally with the legs a and lock the parts of the easel 105 together.

It will be seen that the front element of the easel, upon which the article to be dis-

played rests and by which it is prevented from sliding forward, is adjustable from one position of inclination relative to the horizontal to another; and also that the rear element, against which the back of the article is supported, is adjustable from one position of inclination to another. This is clearly indicated in Fig. 4 where three positions of the parts of the easel are indicated—the positions indicated in Figs. 2 and 3 in dotted lines, and an intermediate position in full lines. The positions which the elements assume and in which they are maintained depend upon the positions to which the connecting devices C are adjusted along the bars or legs of the rear element; and when the parts C are moved upward the upper or article-supporting end of the rear element is brought forward relative to the front element, thereby changing the inclination at which the article is held. The two elements of the easel are also vertically adjustable, the rear element being higher in the position indicated in Fig. 2 than it is when in either of the positions represented in Fig. 3 or 4, its bearing point or resting surface for the article being correspondingly raised. The front element is higher in Fig. 3 than it is in either Fig. 2 or 4.

30 What I claim is:—

1. A display easel for an article like a plate having a front element upon which the lower edge of the article rests and a rear element against which the rear surface of the article bears, the front element being at the rear adjustable vertically to either of several positions on the rear element, substantially as set forth.

2. A display easel having a front element arranged to be adjusted vertically and formed with devices for receiving the lower edge of the article and preventing it from slipping, and a rear element arranged also to be adjusted from one position to another vertically and to contact at its upper end with the upper portion of the article and support the same, and united by a sliding connection to the front element, the sliding connection being movable vertically, whereby the distance between the said article-receiving device of the front element and the article contacting point of the rear element is variable at will.

3. A display easel having a front element arranged to be adjusted vertically and formed with devices for receiving the lower edge of the article and preventing it from slipping, and a rear element arranged also to be adjusted from one position to another vertically and to contact at its upper end with the upper portion of the article and support the same, and united by a sliding connection to the front element, the sliding connection being movable vertically, whereby the distance between the said article-receiving

device of the front element and the article-contacting point of the rear element, and the inclination of the article, are variable at will.

4. A display easel having a generally horizontal front element adapted to sustain a dish or other article and to prevent it from slipping forward thereon, and a rear element having an upright for contacting with and supporting the back part of the dish or other article, said rear element being connected to the front element by a sliding union, and being adapted to be inclined to and supported in either of several positions relative to the vertical, substantially as set forth.

5. A display easel having a front element adapted to sustain a dish or other article, and provided with means to prevent the dish from slipping forward, and a rear element against which the article bears connected with the front element by a sliding union, and adjustable to either of several positions relative to the vertical, and also adjustable to either of several positions forward and back relative to the front element, substantially as set forth.

6. A display easel having a front element with vertically adjustable side bars for sustaining a dish or other article, and a rear element having its dish sustaining part adjustable forward and back in relation to the front element, and a movable uniting device between the front element and the rear element arranged to be adjusted from one position to another, substantially as set forth.

7. A display easel having a front element arranged to be adjusted vertically and formed with devices for receiving the lower edge of the article and preventing it from slipping, and a rear element arranged also to be adjusted from one position to another vertically and to contact at its upper end with the upper portion of the article and support the same, and united by a sliding connection to the front element, the sliding connection being movable vertically, whereby the inclination of the article is variable at will.

8. A display easel having a rear element formed of a wire or metal strip bent to provide two vertical legs and the supporting feet, one at the bottom of each leg, and the front element formed of a wire or strip bent to provide the side bars, the table engaging support or feet, and the cross connecting device between the side bars, and the adjustable connecting device between the front element and the rear element, substantially as set forth.

9. A display easel having a front element formed with side bars b, b, a cross connecting bar c and table engaging feet or supports c', a rear element having vertical legs and table engaging feet, and means for adjusting the side bars of the front element to either of

several positions on the legs of the rear element, substantially as set forth.

10. A display easel having a rear element formed of a wire bent to have legs *a* connected at the top, said element being adapted to be adjusted to either of several positions in relation to the vertical, and a front element having side bars, a cross connecting bar and a table engaging support, said side bars being adjustably connected to the rear element and adapted to be inclined to different positions corresponding to the differing positions of the rear element, substantially as set forth.
15. 11. A display easel having in combination elements A and B, the element B being arranged to be moved upward and downward around its front ends as a center into either of several positions, and the element A being 20 arranged to be moved simultaneously forward and backward respectively relative to

the element B into either of several positions, the said elements during such adjustment being permanently united together by sliding connections, substantially as set forth.

12. A display easel having a front element for contacting with and supporting the lower part of the article, and a rear element for contacting with and supporting the upper part of the article, the rear end of the front element being vertically slidably connected with the rear element, and the parts being so arranged that the weight of the article locks the said sliding connection in any predetermined position of adjustment.

In testimony whereof I affix my signature in presence of two witnesses.

JAMES E. TWITCHELL.
